CLAIM

The ornamental design for an electrical receptacle tester, as shown and described.

DESCRIPTION

FIG. 1 is a top, first side perspective view for an electrical receptacle tester in accordance with the present invention; FIG. 2 is a top, second side perspective view thereof; FIG. 3 is a side elevational view of the first side thereof; FIG. 4 is a bottom perspective view thereof; and, FIG. 5 is a top view thereof shown in FIG. 1.

The broken line in the drawing views represents unclaimed environment and forms no part of the claimed design.
